UNITED STATES PATENT OFFICE.

WILHELM GRAAFF, OF BERLIN, GERMANY.

ICE-MAKING MACHINE.

1,101,694.

Specification of Letters Patent. Patented June 30, 1914.

Application filed September 26, 1911. Serial No. 651,395.

To all whom it may concern:

Be it known that I, WILHELM GRAAFF, merchant, a subject of the German Emperor, and residing at 17 Linkstrasse, Berlin, W. A., in the Kingdom of Prussia, Germany, have invented certain new and useful Improvements in Ice-Making Machines, of which the following is a specification.

The present invention relates to improvements in still-absorbers acting alternately as distiller and absorber or condenser and refrigerator. Machines of this kind are described in the U. S. Patent No. 958,683.

The subject matter of this invention resides in a still absorber of this type provided with an inner shell surrounded by an outer jacket leaving a space between them containing the heating or cooling medium respectively. This jacket may be connected to the shell in an easily detachable manner or be rigidly secured thereto. When the still-absorber is rotated, as is the case with the ice making machine according to the U. S. Patent No. 958,683 the entrance for the cooling medium is preferably admitted in the axial direction of the vessel to be cooled, and so arranged that the said vessel can be rotated together with its jacket without the flexible tube serving for the supply of the cooling medium, participating in such rotation.

In the accompanying drawing one embodiment of the present invention is illustrated and: Figure 1 shows in longitudinal section the still-absorber as constructed for an ice making machine according to U. S. Patent No. 958,683 and; Fig. 2 a sectional view of the device for closing the entrance for the cooling medium; and Fig. 3 a sectional view of a detail in larger scale.

In the drawing, *a* is the shell of the still-absorber for an ice making machine and *b* is a jacket surrounding the shell leaving a space between them. In the constructional form shown this jacket is connected in an easily detachable manner with the vessel *a*. For this purpose it is fitted with a sleeve *c*, which is mounted to revolve in a bearing *d*. This sleeve fits closely over the trunnion *e* of the vessel or shell *a*. The trunnion *e*, arranged axially with the shell *a*, is hollow and is provided with a screw threaded stopper for closing the shell when emptied. The trunnion *e* has longitudinal ducts *o*, communicating with the space between the shell *a* and jacket *b* when assembled for the

insertion of the cooling or heating medium respectively. Upon assembling the jacket over the shell the sleeve *c* fits closely around the trunnion *e*.

The jacket *b* is provided with a drain pipe *h*, having suitable closing means which is only used during the heating period of the machine. This closing means comprises a hood *q*, suitably threaded to be screwed on or otherwise securely fastened over the drain pipe *h*, and comprising the gasket *r*. The hood is provided with a safety valve *s* opening outward. A spring *v* around the valve spindle *t*, acting between a shoulder *w* and a nut *u*, tends to keep the valve closed. By tightening or loosening the nut *u*, the compression of the spring may be varied as required, so that the time for opening the valve may be regulated in accordance with the permissible pressure for the heating medium in the jacket *b*. Whenever the jacket *b* is to serve as "cooling-jacket," the hood *q* is removed to permit a quick and free flow of the cooling medium through the jacket. The sleeve *c* is provided with an opening *i* at its free end. In front of this opening is arranged a nipple *k*, over which lies a spring *m* which bears with one end on a cap *n* secured on the sleeve *c*, by means of a screw thread, and with its other end on a flange of the nipple *k* so that the latter is pressed securely and forming a tight joint against the sleeve *c*. By this means of connecting the nipple *k* and the sleeve *c* it is possible to rotate the latter together with the shell *a* and the jacket *b*, while the nipple remains stationary. The cooling liquid entering through the nipple *k* into the sleeve *c* can pass through the passages *o* into the space between the jacket *b* and the shell *a*. After the cap has been loosened, the nipple *k* can be removed from the sleeve *c* and in its place the tightly closing cap *p*, see Fig. 2, may be substituted.

In order to make a firm connection between the jacket *b* and the shell *a*, elbow shaped latches are provided near the right end of the jacket *b*, which consist of a lever *f*, mounted to turn on the jacket. At the end of the short arm of these levers *f* are provided U-shaped eyelets which engage over hoops on the ring *g*, attached to the shell *a*. By turning the lever *f* toward the left of the drawing this clamping arrangement is loosened, releasing the ring *g*, whereupon the shell *a* may be removed from the jacket.

At the right hand end of the shell is provided a pipe in alinement with the trunnion, at the opposite end thereof, which pipe connects with the condenser evaporator. 5 A heating jacket is provided around the shell *a*, leaving a space between the jacket and the shell in order to prevent over-heating and consequent destruction of the absorbing means contained in the shell *a*. Before starting the heating operation a fluid, 10 such as brine or oil is for this reason injected into said space.

The apparatus operates in the following manner: When during the distilling period, 15 the shell *a* is to be heated, the cap *p* is secured on the sleeve *c* and a heat transmitting medium such as water, brine or oil is filled into the space between the shell *a* and jacket *b*. The pipe *h* is now closed by means of a 20 valve and the jacket heated. Any vapors from the heat transmitting medium may escape through the safety valve in the pipe *h*. As soon as the jacket *b* has been heated sufficiently and the absorbing period is to be 25 commenced, the safety valve is closed tightly, the cap *p* is thereupon removed from the trunnion and replaced by the cap *m* with the nipple *k*. The cooling liquid is now allowed to enter through the nipple *k*, the 30 sleeve *c*, and passages *o*, into the space between the shell *a* and jacket *b*. When the machine is now being rotated this cooling liquid will flow around the shell *a* and escape through the pipe *h*. Obviously the jacket 35 and shell, instead of being constructed in two parts as shown on the drawing may be made integral; or the jacket may be made stationary permitting the vessel or shell to rotate inside it. In the latter case the cooling 40 medium would be entered at the top of the jacket and means provided to distribute it over the whole length of the inner vessel.

I claim:

1. In a still-absorber, an inner vessel, a jacket surrounding said vessel leaving an intervening space between them, an entrance for the cold transmitting medium, a cap for temporarily closing said entrance, an opening in said jacket for draining off said medium, and a closure for said opening containing a safety valve. 45

2. In a still-absorber, a rotatable vessel, a jacket connected thereto and surrounding it so as to leave an intervening space between them, a coupling admitting of introducing 55 the refrigerating medium into the space between said vessel and said jacket during the rotation of the machine and an outlet from said jacket and detachable means for rigidly holding jacket and vessel together. 60

3. A still-absorber comprising an inner vessel and a surrounding jacket, a space formed between the vessel and the jacket for a cold transmitting medium, an outlet from said vessel and, in axial alinement therewith, 65 a trunnion on said vessel; a sleeve in said jacket adapted to fit closely around said trunnion and a bearing in which said sleeve with the trunnion may revolve; a nipple 70 revolvably mounted on said sleeve, and a cap adapted to replace said nipple for closing the sleeve; said trunnion having passages for admitting cold transmitting medium entering said nipple, into said space; clamping means at the opposite end of the jacket for 75 securing said vessel centrally therein; a radial outlet on said jacket for said medium and a safety valve in said outlet.

In testimony whereof I affix my signature in presence of two witnesses.

WILHELM GRAAFF.
